UNITED STATES PATENT OFFICE.

E. G. ATWOOD, OF DERBY, CONNECTICUT.

SKELETON SKIRT.

Specification forming part of Letters Patent No. 21,806, dated October 19, 1858; Reissued July 26, 1859, Nos. 784 and 785.

To all whom it may concern:

Be it known that I, E. G. Atwood, of Derby, in the county of New Haven and State of Connecticut, have invented a new and useful Improvement in Skeleton Skirts; and I do hereby declare that the following is a full, clear, and exact description of the same, reference being had to the accompanying drawing, making a part of this specification, in which—

Figure 1 is a side view of a skirt constructed according to my invention. Fig. 2 is a view on a larger scale than Fig. 1, of parts of three hoops, showing the manner 15 of connecting and suspending them.

Similar letters of reference indicate corresponding parts in both figures.

The nature of my invention consists in a skirt formed of tape or similar material and 20 a series of circle hoops, when the tape is passed over one hoop and under the next below it in opposing oblique directions and the tapes fastened at the points where they interlock on the hoops themselves by clasping, sewing or tying. By this method of 25 constructing a skirt the hoops are entirely supported by the tapes or straps without depending upon the strength of the clasps, sewing or the tying by which the tapes are 30 held in proper position on the hoops and thus increased durability is secured. The oblique arrangement of the straps or tapes gives a more steady motion to the skirt and carries the dress more evenly and 35 symmetrically as the straps are disposed more universally throughout the skirt in a manner to give the dress a support at every point. Said oblique arrangement also prevents that 40 painful swinging or wiggling of a lady's dress so common to those skirts having the straps placed perpendicularly and not braced laterally or diagonally. These benefits, I am aware are not altogether peculiar to my skirt, for in the knit fabric the threads 45 fill up all the spaces between the hoops, the thread running diagonally and tying or interlocking midway of the spaces between the hoops. This construction of knit skirt gives as perfect and symmetrical set to the 50 dress as mine, but there are objections to its use because it hangs into objects and has its meshes broken and when one mesh breaks there is nothing to prevent a series of others giving way with it and the consequent formation of a very large rent, whereas, with

my skirt, the angles of the tapes are independent of each other and when one angle is broken, none of the other angles are affected thereby; this results from confining the interlocking portions of the tapes on the 60 hoops by clasps sewing or tying. One of my skirts with eleven hoops will, owing to the peculiar universal disposition of the tapes or straps answer as well, if not better for all purposes than a skirt with thirteen hoops. 65

A, A, are the hoops which extend all around the skirt and which may be of any kind commonly used.

B, B, are springs which form the "bustle."

C, C, are the straps which connect and 70 suspend the hoops. The manner of applying these straps is best illustrated in Fig. 2, where the metal clamps are omitted and where it will be seen that each strap is passed over one hoop, then obliquely down 75 to and under the one below it, and thence obliquely in the opposite direction up to and over the first one, and so on continuously all the way or as far around the hoops as may be desired. This arrangement forms a 80 series of loops where the straps pass over and under the hoops and each strap is passed over and under its respective hoops so as to interlace with the loops of the straps above and below it, excepting of course the 85 top and bottom straps the former of which can only pass through loops in a strap below and the latter through those in the strap above as will be obvious. The several tapes thus combine to form as it were a lattice-work, which gives a more nearly continuous 90 support to the garment outside it than when the straps are arranged vertically, and which thus makes the skirt very superior. 95 In the skirt represented in Fig. 1, this arrangement of straps is discontinued in a portion of the front where the lap joints in the hoops are made to permit the circumference of the hoops to be adjusted or varied, and straps D, D, running directly up and 100 down are employed in this portion of the skirt.

a, a, (Fig. 1) are the metal clamps, which are composed simply of narrow strips of metal plate of a length sufficient to lap 105 nearly or quite around the width and thickness of the hoops. These clamps are applied around the hoops and straps at the points where the loops in the latter hang on and suspend the former and also to form 110

junctions between the extremities of the straps and the hoops; the said clamps being pinched tightly upon the hoops and straps so as to attach them securely and prevent 5 any slipping either of the straps or hoops.

I do not confine myself to any form for the metal clamps a, a .

What I claim as my invention and desire to secure by Letters Patent, is—

- 10 A skirt formed of tape or similar material and a series of circle hoops, when the tape

is passed over one hoop and under the next below it in opposing oblique directions and the tapes fastened at the point where they interlock on the hoops themselves by clasping, sewing or tying, substantially as and for the purposes set forth. 15

E. G. ATWOOD.
